UNITED STATES PATENT OFFICE.

JOHN W. SHARP, OF CHICAGO, ILLINOIS.

SAFETY SYSTEM FOR RAILWAYS.

No. 926,214.

Specification of Letters Patent. Patented June 29, 1908.

Application filed April 15, 1908. Serial No. 427,116.

To all whom it may concern:

Be it known that I, JOHN W. SHARP, citizen of the United States, residing at Chicago, in the county of Cook, State of Illinois, have 5 invented certain new and useful Improvements in Safety Systems for Railways; and I do hereby declare the following to be a full, clear, and exact description of the invention, such as will enable others skilled in the art to 10 which it appertains to make and use the same.

This invention has for its object to provide very simple and efficient means whereby a railroad train either passenger or freight 15 besides being in control of the engineer, is placed in control of the remainder of the train crew and also of switchmen and depot hands, and consists in the features of construction and combinations of parts herein- 20 after fully described and claimed.

In the accompanying drawings illustrating my invention: Figure —1— is a view in side elevation of a locomotive and tender equipped with safety devices constructed in accordance with my invention. Fig.—2— is a fragmentary plan view of the track, and showing diagrammatically the train pipe of the locomotive and tender in its relation to movable stops disposed on the track. Fig.—3— is a diagrammatic view of a caboose equipped with train controlling means in accordance with my invention. Figs.—4— and —5— are respectively a fragmentary plan view and side elevation showing a trip disposed in the track 30 and means for operating the same. Fig.—6— is a central vertical longitudinal section on the line 6—6 of Fig.—7— of an exhaust valve disposed in operative connection with the train pipe of the locomotive and tender. Fig.—7— 35 is a side elevation of said valve. Fig.—8— is a central longitudinal section of the air brake controlling valve disposed in the caboose. Fig.—9—

It is well known that many wrecks, particularly of freight trains, are caused by the 45 carelessness of the train crew in making up the train and usually consisting in omitting to connect all of the cars in the air brake system. That is to say that generally not more than 75 per cent. of the cars are so connected as to 50 make the air brakes thereof operative, and sometimes this percentage is very materially decreased. Except by careful inspection the yard-master or the conductor cannot ascertain just how many cars are under air and

though the air brake hose may be coupled 55 throughout, the shutting off of a stop-cock in the train pipe at any point will place all cars rearwardly of said cock entirely out of direct control.

A long and heavy freight train can be 60 properly and safely handled only when all cars in the train are under air and the primary object of my invention is to provide means whereby any member of the crew may easily ascertain whether this is the case 65 and also the pressure carried in the air brake system besides enabling such member to set the brakes from the rear end of the train so that in the event that the engineer shall fail to obey a signal from any cause whatsoever, 70 a member of the crew may at once set the brakes and stop the train.

Passenger trains are at present equipped with means whereby the brakes may be set from any car in the train, such means being 75 operable by a rope running through the train, but said means, while fairly efficient, are not entirely reliable for the reason that said rope may break, and again the crew member attempting to stop the train may not release 80 the hold on said rope until the train shall have stopped for fear that the engineer and firemen may not heed the signal thus conveyed while on the other hand said crew member can perform no other service such as 85 in an emergency may be required of him owing to the urgent necessity of holding on to said rope until the train has been stopped.

My invention contemplates the provision of means whereby the crew member may 90 set an exhaust valve by a simple operation and thus be free, while the train is stopping, to perform other service, such means being equally applicable to both passenger and freight trains but intended more particularly for the latter for the reasons above set forth.

My invention also has for its object to provide simple and efficient means on the train and on the railway and controllable 100 by a switch tender or depot hand to bring a train to a stop in the event that a stop signal should be disregarded by all members of the train crew, the last named object being, however, of least importance.

The invention consists more particularly in the specific means provided for proper control of the train, said means including

valves of particular forms of construction whereby efficiency is assured.

It is well known that cabooses at the tail ends of freight trains are not equipped with air brakes, and therefore, are devoid of train pipes. For the purpose of carrying out my invention I equip the caboose A with a train pipe B having stop-cocks C interposed in the ends thereof and equipped at its ends with the usual flexible hose D and couplings to enable said pipe to be brought into the air brake system. Between its ends said pipe B is connected with a pipe E passing into the cupola of the caboose and which there 15 communicates with an exhaust valve F of a particular form of construction, illustrated in Fig. --8--, said valve being connected at its discharge end with a pipe G discharging underneath the car. The said valve F 20 comprising the casing provided midway between its ends with a tapered opening in which the tapered plug or valve H fits and is secured in a manner common to valves of this class. The inlet passage I extends vertically through the casing and communicates at its opposite ends with the pipe E and a pressure gage J. Between its ends said passage I communicates with a lateral passage K controlled by the said valve H between 25 its ends and connecting at its other end with the vertical passage L connecting with the pipe G. The said pressure gage enables the conductor or other member of the crew to ascertain the working pressure and by 30 means of said valve F it is easy to ascertain whether the entire train is under air and whether all stop cocks are sufficiently open to insure efficiency. Furthermore by opening said valve F he can apply the air brakes. 35 40 and in case of emergency may set said valve open and jump from the train or run along the tops of the cars to the engine in order to inform or instruct the engineer or signal the latter. The train being thus under control from both ends there is slight possibility of accident due to any neglect of the crew but in order to place a further check on the crew I prefer to also provide means whereby the train may be stopped by a switch tower 45 50 operator or station hand, said means comprising exhaust valves M connected with the train pipe of the locomotive and tender and adapted to be opened by obstructions in the track operable from a switch or signal tower or station, said obstructions consisting of substantially V-shaped projections N rigidly mounted on horizontal rock shafts O extending transversely of the rails and provided at one end with a cross bar P 55 60 to which the ends of wires or cables Q are secured, the latter being suitably connected with operating means disposed in the tower or other building R and by means of which said shaft may be turned through an arc of 65 ninety degrees to throw said projection N

either into vertical or horizontal position. Springs S are interposed in said cables Q in order to render said obstructions yielding the strength of said springs being such as to resist the force of the blow of the stem T 70 of a valve M in the path of which it is disposed but enabling said obstruction to yield to greater force applied as, for example, from a broken brake beam or the like. The said valves M are also of the tapered valve pattern 75 and the valve stems T thereof depend vertically to maintain said valves normally closed.

Secured at one end to the casing of each valve is a flat spring U the free end portion 80 of which is substantially semi-circular and disposed substantially concentric with the axis of the valve, said semi-circular portion being bulged outwardly between its ends. The extreme free end of said spring U bears upon the said valve stem or lever T and when the latter is turned by contact with one of said obstructions to open the valve, the free end of said spring springs over the said lever which thus becomes engaged by 85 said bulged semi-circular portion of said spring and is prevented by the latter from returning to its closed position by reason of the jarring and vibration of the locomotive. Said obstructions may be placed at any desired intervals in the track and disposed adjacent relatively opposite rails so that both the oppositely disposed valves M are operated thus guarding against the possibility that one of said valves may fail to perform 90 its proper function. This, however, is deemed unnecessary, obstructions adjacent one rail being sufficient, but it is essential that the two oppositely disposed valves be employed so that one of same shall be operated whether the locomotive is traveling 95 forward or rearward.

To insure proper operation of the valves I provide an opening V in the casing for the introduction of oil, said opening being normally closed by a plug W. The use of said obstructions is essential to insure greater safety of passenger traffic, the train crews of passenger trains being unable, unlike the crews of freight trains, to look ahead from the cupola of a caboose to keep a check on the engineer and, hence, this duty must rest with switch tenders and depot hands. It is also essential that said valves M shall be so disposed as to be entirely out of reach of the 110 engineer or fireman while the train is running so that said valves cannot be locked or tampered with by the latter, it being well known that many engineers are very reckless and heedless of danger.

By the means above described railroad travel may be rendered almost entirely safe.

In developing said means I have kept in mind very particularly the avoidance of expensive and complicated equipment and be-

lieve that the cost of equipment in accordance with my invention would not be burdensome:

I claim as my invention:

- 5 1. In a railway train, a rear end car such as a caboose equipped with a train pipe and having air brake connection with the locomotive, a pipe connected with said train pipe between the ends of the latter, an exhaust valve interposed in said pipe and disposed within the cupola of said caboose, said valve comprising the valve casing equipped between its ends with the valve and having inlet and outlet passageways on opposite sides of 15 the latter and communicating therewith through a lateral passage controlled thereby, said inlet passage extending through said casing, and a pressure gage connected with one end of said inlet passage.
- 20 2. In a railway movable obstructions disposed in the track and operable from a switch tower or the like, springs operatively disposed in the means operating the said obstructions to yieldingly support the latter, exhaust valves disposed on the train in the air-brake system thereof, operating levers on said exhaust valves adapted to be actuated by said obstructions to open said valves and set the brakes, and springs operatively
- 25

engaging said operating levers to prevent 30 return thereof to normal position to close said valves.

3. In a railway movable obstructions disposed in the track and operable from a switch tower or the like, springs operatively 35 disposed in the means operating the said obstructions to yieldingly support the latter, exhaust valves disposed on the train in the air-brake system thereof, operating levers on said exhaust valves adapted to be actuated 40 by said obstructions to open said valves and set the brakes, and springs operatively engaging said operating levers to prevent return thereof to normal position to close said valves; an exhaust valve within a car of the 45 train similarly interposed within the air brake system and operable by a member of the crew other than the locomotive crew to set the brakes, said respective exhaust valves serving to maintain a double check 50 on the locomotive crew.

In testimony whereof I have signed my name in the presence of two subscribing witnesses.

JOHN W. SHARP.
